CLAIM

The ornamental design for catamenial pads, as shown and described.

DESCRIPTION

FIG. 1 is a front perspective view of a first embodiment of catamenial pad showing our new design;

FIG. 2 is a rear perspective view of the embodiment of FIG. 1;

FIG. 3 is a left side view of the embodiment of FIG. 1, a right side view being a mirror image thereof;

FIG. 4 is a front elevation view of the embodiment of FIG. 1;

FIG. 5 is a rear elevation view of the embodiment of FIG. 1;

FIG. 6 is a top plan view of the embodiment of FIG. 1;

FIG. 7 is a bottom plan view of the embodiment of FIG. 1;

FIG. 8 is a front perspective view of a second embodiment of catamenial pad showing our new design;

FIG. 9 is a rear perspective view of the embodiment of FIG. 8;

FIG. 10 is a left side view of the embodiment of FIG. 8, a right side view being a mirror image thereof;

FIG. 11 is a front elevation view of the embodiment of FIG. 8;

FIG. 12 is a rear elevation view of the embodiment of FIG. 8;

FIG. 13 is a top plan view of the embodiment of FIG. 8;

FIG. 14 is a bottom plan view of the embodiment of FIG. 8;

FIG. 15 is a front perspective view of a third embodiment of catamenial pad showing our new design;

FIG. 16 is a rear perspective view of the embodiment of FIG. 15;

FIG. 17 is a left side view of the embodiment of FIG. 15, a right side view being a mirror image thereof;

FIG. 18 is a front elevation view of the embodiment of FIG. 15;

FIG. 19 is a rear elevation view of the embodiment of FIG. 15;

FIG. 20 is a top plan view of the embodiment of FIG. 15; FIG. 21 is a bottom plan view of the embodiment of FIG. 15;

FIG. 22 is a front perspective view of a fourth embodiment of catamenial pad showing our new design;

FIG. 23 is a rear perspective view of the embodiment of FIG. 22;

FIG. 24 is a left side view of the embodiment of FIG. 22, a right side view being a mirror image thereof;

FIG. 25 is a front elevation view of the embodiment of FIG. 22;

FIG. 26 is a rear elevation view of the embodiment of FIG. 22;

FIG. 27 is a top plan view of the embodiment of FIG. 22; and,

FIG. 28 is a bottom plan view of the embodiment of FIG. 22.
